[57] CLAIM

The ornamental design for a combined wristwatch and strap, as shown.

DESCRIPTION

FIG. 1 is a front elevational view of a combined wristwatch and strap showing my new design;

FIG. 2 is a rear elevational view;

FIG. 3 is a left side elevational view;

FIG. 4 is a right side elevational view; and

FIG. 5 is a top plan view, the bottom plan view being a mirror image thereof.

FIG. 5
